 corporation of Michigan

Application September 27, 1947, Serial No. 776,497

6 Claims. (Cl. 200—153)

1

The present invention relates to an electrical switch of the type particularly adapted for operation by a mechanical means, such as the moving part of a machine, a system of levers or a mechanical timing device.

It is the general object of the present invention to provide a switch of the type mentioned characterized by its extreme simplicity, low cost and ease of assembly.

Other objects and advantages of the invention will become apparent from the following specification, the accompanying drawing and the appended claims.

In the drawing:

Figure 1 is a rear elevation of the switch, showing the same mounted on a supporting panel;

Figure 2 is a sectional view taken on the line 2—2 of Figure 1;

Figure 3 is a sectional view taken on the line 3—3 of Figure 1;

Figure 4 is an exploded view, showing in perspective all of the parts forming the switch; and

Figure 5 is a fragmentary section taken on the line 5—5 of Figure 3.

The principles of the invention are shown in the drawing as incorporated in a normally open single pole switch of the type employing two pairs of mating contacts which are connected in parallel and which successively engage when the switch is closed and successively disengage in the reverse order when the switch is opened, thus insuring that any arcing at the contacts will always occur at one pair of engaging contacts and leaving the other pair of contacts free of any impairment which would otherwise adversely affect their current carrying capacity. It will be appreciated, however, that the principles of the invention are applicable to other forms of switch mechanisms, such as normally closed switches or switches which incorporate only one pair of engageable contacts.

As shown in the drawing, the complete switch assembly comprises a pair of mating housing sections, indicated generally at 1 and 2, within which are supported a stationary contact element 3 and a movable contact element 4. The movable contact is actuated by means of a button 5, which projects through a suitable opening in the housing and is actuated by one end of a reversely bent leaf spring 6.

An important feature of the invention resides in the fact that the housing sections 1 and 2 are identical to each other, with the result that both may be formed on the same set of dies from any suitable material, such as a molded plastic. Each

housing section includes a contact receiving recess 7 formed in the face 8 which mates with the corresponding face of the other section. The recess 7 is connected by means of a pair of slots 9 and 10 to the rear face 11 of the section. The recess 7 is also connected by a semicircular slot 12 to the front face 13 of the section, and the bottom of the recess is formed with three aligned spaced grooves or recesses 14, 15 and 16, which, as hereinafter pointed out, serve to locate and support the contact elements within the housing sections on assembly. The housing sections may be secured together in any suitable manner, such as by a pair of bolts, which bolts are adapted to pass through openings 17 and 18 formed therein. It will be noted that the openings 17 are countersunk to receive a raised annular boss 19 formed on the face 8 of each section around the opening 18 therein. As a result of this construction, the engagement of the bosses 19 within the countersunk portions of the openings 17 prevents relative displacement between the housing sections 1 and 2 in a plane parallel to the mating faces 8 and eliminates the necessity of having a close fit between the openings 17 and 18 and the bolts 20 which secure the housing sections together and to any suitable supporting member, such as the plate 21.

The stationary contact element 3 comprises a single flat plate 22 having a pair of contact elements 23 and 24 fixedly secured thereto. The plate 22 is formed of any electrically conductive material, such as copper or brass, and is provided with two pairs of oppositely extending ears 25 and 26. The contact elements 23 and 24 are secured to the plate by riveting, and the contact 23, which is, in itself, in the form of a rivet, serves to secure a terminal 27 to the plate, in the manner best shown in Figure 2.

The movable contact element 4 comprises a supporting plate 28, which is generally rectangular in form and of the same dimensions as the portion of plate 22 which includes the ears 26 and contact 24. A spring bronze or other suitable electrically conductive flexible contact arm 29 and a terminal 30 are fixed to the plate 28 by means of a double ended rivet 31, the arm 29 and the plate 28 being held in spaced relation by a head 32 located intermediate the ends of the rivet. The arm 29 has riveted thereto a pair of contact elements 33 and 34, the former being located intermediate the ends of the arm and the latter adjacent the outer extremity thereof.

A further important feature of the invention resides in the fact that the symmetrically ar-

ranged recesses 14 and 16 in the identical housing sections 1 and 2 may, due to the construction and arrangement of the contact elements 3 and 4, serve to locate and support either one of the contact elements interchangeably. Thus, if the parts are assembled while they are in the relative positions indicated in the exploded view of Figure 4, the ends of plate 28 are fitted within the notch 14 in section 1 and the notch 16 in section 2, while the ears 26 on the contact element 3 are fitted in the notch 16 of section 1 and the notch 14 of section 2, in the manner best shown in Figures 2 and 3. However, if desired, the position of the contact elements 3 and 4 may be reversed without in any way changing the construction or mode of operation of the final assembly. In that case, the ends of the plate 28 are fitted within the recess 16 in housing section 1 and 14 in housing section 2, while the ears 26 are fitted within the recess 14 of section 1 and 16 of section 2. In either case, the ears 25 of section 3 fit within the recesses 15 of both housing sections and in both cases the terminals 27 and 30 will lie in the openings formed by the mating slots 9 and 19. The fact that the contact elements may be interchangeably positioned within the housing greatly facilitates assembly, since the parts cannot be assembled in an improper relationship and it is unnecessary to manipulate the housing sections to one of the two possible positions in order to achieve a successful assembly.

When the switch is assembled, the button 5, which is an entirely loose piece, is inserted in position with its projecting end extending through the opening formed by the mating notches 12. The external operating spring 6 has a U-shaped end portion 35, which is adapted to fit within an L-shaped recess 36 which is formed in the face 8 of each housing section and which opens to the front face 13 of each section. The width of the spring 6 is almost twice the depth of the recess 36 formed in each section, with the result that on assembly the spring lies on opposite sides of the plane containing the mating faces 8 of the housing sections. The U-shaped end of the spring loosely fits within the L-shaped recess 36 and forms, in effect, a pivotal mounting for the end of the spring. The connection thus afforded between the spring and the housing cannot be disconnected without separating the housing sections. The opposite end of the spring is provided with a U-shaped section having a terminal portion 37 which engages the operating button 5.

It will be understood that the spring 6 may be omitted if desired, and the switch operated by direct actuation of the button 5. However, since in mechanically operated switches of the type here involved it is frequently difficult to eliminate overtravel of the mechanical device which operates the switch, it is desirable to provide, in connection with the switch mechanism, means to permit such overtravel without damage to the switch, itself. For that purpose, the spring 6 is provided. Thus, on application of a switch actuating force to the spring in the direction indicated by the arrow in Figure 2, the switch contacts will engage and thereafter the spring may further distort to permit overtravel, if any, in the operating mechanism which exerts the force. It will be observed that since the switch closing force is applied by button 5 to the central portion of the flexible arm 29, the contact element 34 will engage its mating contact element 24 before engagement between the contacts 33 and 23 occurs. Conversely, as the switch is opened, contacts 33 and 23 will disen-

gage before disengagement of contacts 34 and 24 occurs. Consequently, all of the arcing will occur at the contacts 24 and 34. This will leave the surfaces of the contacts 23 and 33 unpitted and thus prevent impairment of their current carrying capacity. The contacts 24 and 34 are provided solely for the purpose of taking the arcing on closure and opening of the switch in the manner described above, and are otherwise unnecessary since all of the current may be carried by the contacts 23 and 33.

It will be noted that since the two housing sections 1 and 2 are identical, there are two sets of recesses 36 in each housing. This permits mounting of the spring 6 at either end of the housing without changing the mode of operation or characteristics of the device. The external mounting of the leaf spring 6 is particularly advantageous in that it permits direct observation and adjustment of the amount of overtravel provided thereby. As a result, damage to the switch mechanism due to excessive overtravel in the operating mechanism is easily avoided.

A further feature of the invention resides in the detailed construction of the notches or recesses 14 and 16. As best shown in Figure 5, the notch 16 is of greater width than the ears 26 on plate 22. However, one side of the notch is formed with a centrally located projection 37 while the opposite side is provided at each end with a pair of projections 38. The arrangement is such that when the ears 26 are forced into the notch or recess, the projections 37 and 38 bend the ears in the manner best shown in Figure 5. For this purpose the outer ends of the projections are slightly rounded or inclined in order to bend the ears by a camming action as they are forced into the recess.

It will be understood that the notch or recess 14 is constructed in the same manner as notch 16 and similarly coacts with the ends of plate 28. Also plates 28 and 22 are of the same thickness with the result that plate 28 may be fitted in either notch and the ears on plate 22 in the other.

Two important advantages flow from the above described notch or recess construction. In the first place, the projections 37 and 38 positively grip the ears 28 and the ends of plate 28 and thus hold the associated contacts in a fixed position within the housing independent of variations in the thickness of the plates 22 and 28 and the width of the notch which result from normal manufacturing tolerances. Secondly, the friction induced by the tendency of the bent ears and bent ends of plate 28 to return to a flat condition holds the two housing sections together sufficiently to permit normal handling of the assembled switch prior to insertion of the permanent fastening means (rivets or bolts) through openings 17 and 18.

While, as shown in the drawings and described above, the notches 14, 15 and 16 are recessed below the bottom surface of the recess 7, it will be apparent that this is not necessary since the surfaces which engage the plates 22 and 28 and hold them in position may be formed on projections extending above the general level of the bottom of recess 7 without changing the principle or advantages of the invention.

While only one form of the invention is shown and described herein, it will be apparent that variations in the details of construction may be indulged in without departing from the spirit of the invention or the scope of the appended claims.

What is claimed is:

1. A switch, comprising a housing formed of two identical sections having mating recesses forming an internal chamber for the reception of relatively movable switch contacts, said sections having mating slots through the side walls of said recesses adapted to receive switch terminals, a pair of switch contact elements each having a supporting portion and a pair of equally spaced contact portions and a terminal, the contact portions on one of said elements being fixed to a flexible strip one end of which is fixed to the supporting portion of said element, the supporting and contact portions being located within said chamber and the terminal portions lying in said mating slots, the contact portions on the flexible strip being so positioned that on flexure of said strip in one direction the contacts on one element engage the contacts on the other in succession and on flexure in the opposite direction said contacts disengage in the reverse order, each of said housing sections having surfaces formed to engage the supporting portion of each of said contact elements and support the elements in proper relative position, each housing section being symmetrical with respect to a central plane extending transversely thereof so that said contact elements may be reversed without altering the relative positions of the contact portions of said elements, and means projecting from the housing for flexing said strip.

2. A switch, comprising a housing formed of two identical sections having mating recesses forming an internal chamber for the reception of relatively movable switch contacts, said sections having mating slots through the side walls of said recesses adapted to receive switch terminals, a pair of switch contact elements each having a supporting portion and a contact portion and a terminal, the contact portion on one of said contact elements being fixed to a flexible strip, one end of which is fixed to the supporting portion of said one of said elements, the supporting and contact portions being located within said chamber and the terminal portions lying in said mating slots, the contact portion on the flexible strip being so positioned that on flexure of said strip in one direction the contact on one element engages the contact on the other, each of said housing sections having surfaces formed to engage the supporting portion of each of said contact elements and support the elements in proper relative position, each housing section being symmetrical with respect to a central plane extending transversely thereof so that said contact elements may be reversed without altering the relative positions of the contact portions of said elements, and means projecting from the housing for flexing said strip in said one direction.

3. A switch, comprising a housing formed of two identical sections having mating recesses forming an internal chamber for the reception of relatively movable switch contacts, said sections having mating slots through the side walls of said

recesses adapted to receive switch terminals, a pair of unitary switch contact elements formed of electricity conducting material and each having a supporting portion and a contact portion and a terminal, the supporting and contact portions being located within said chamber and the terminal portions lying in said mating slots, each of said housing sections having surfaces formed to engage the supporting portion of each of said contact elements to hold said supporting portions in fixed relation to said housing and support the elements in proper relative position, one of said elements being deformable to move the contact portion thereof into engagement with the contact portion of the other of said elements and means projecting from the housing for so deforming said one of said elements.

4. A switch as defined in claim 3 wherein the contact portion and terminal of each contact element is permanently fixed to the supporting portion thereof.

5. A switch comprising a housing formed of a pair of mating sections having recesses which combine to form an internal chamber, and switch mechanism disposed within said chamber mounted on said housing and including a pair of sheet metal mounting plates within said chamber and extending in planes transverse to the plane of juncture of said sections, and a pair of relatively movable switch contacts carried respectively on said plates, each of said sections having surfaces formed in said recesses which distort said plates from their free condition and frictionally engage said mounting plates at opposite sides thereof to hold said plates in a distorted condition.

6. A switch as defined in claim 5, wherein said mounting plates have laterally extending portions received in said recesses and engaged and distorted by said surfaces.
